UNITED STATES PATENT OFFICE.

WILLIAM M. KITCHEN, OF HAVANA, FLORIDA.

CAR-REPLACER.

No. 898,226.

Specification of Letters Patent.

Patented Sept. 8, 1908.

Application filed May 15, 1908. Serial No. 432,967.

To all whom it may concern:

Be it known that I, WILLIAM M. KITCHEN, a citizen of the United States, and a resident of Havana, in the county of Gadsden and State of Florida, have invented certain new and useful Improvements in Car-Replacers, of which the following is a specification.

My invention is an improvement in car replacers, and consists in certain novel constructions and combinations of parts to be hereinafter described and claimed.

Referring to the drawings forming a part hereof, Figure 1 is a plan view of a section of track showing the replacers in position. Fig. 2 is a section on the line 2—2 of Fig. 1.

The present embodiment of my invention comprises a pair of plates A, B, each of said plates being provided on its lower face with legs a, b, for supporting the same, and on its upper face with an integral flange a', b', whose lateral face towards the rail is beveled toward each end thereof as at a², b².

The lateral face of each of the flanges is perpendicular to the upper surface of the plate, and at the point where the two inclined surfaces meet, a friction roller a³, b³, is journaled, the operative face of the roller being inclined with respect to the plate. The upper surface of each of the plates is beveled at its ends as at a⁴, b⁴, and is provided with a handle a⁵, b⁵, for convenience in manipulating the same. The plate A is provided at its opposite edge with a flange a⁶, the lower face of the plate directly below the flange being longitudinally grooved as at a⁷, for engaging the tread c of the rail C. The free edge of the plate B adjacent to the rail is provided with a projecting portion b⁶, which is shaped to fit against the web c' of the rail C, and brackets b⁷ project from the bottom of the plate beneath the rail as shown in Fig. 2.

In operation, the plates are placed as shown in Fig. 1, and the derailed car is moved forward until the flanges of the wheels engage the inclined faces of the flanges a', b'.

The continued movement of the car forces the wheels toward the rails, and as the flanges engage the rollers a³, b³, they trip the wheels dropping them on to the rails with the flanges in proper position. The plates are laid flat upon the ties, and the engagement of the groove of the plate A, with the rail retains the plate A in place, and the plate B is retained in place by the weight of the derailed car, the flange a, of the plate A, receiving the greater part of the stress.

I claim:

1. A car replacer comprising a pair of plates adapted to be placed along side of the rails, each having an integral flange at the side remote from the rail, the lateral face of the flange toward the rail being beveled toward each end thereof, a friction roller at the center of said face, one of said plates having a groove for receiving the tread of the rail, and the other having brackets extending beneath the adjacent rail.

2. A car replacer comprising a pair of plates adapted to be placed along side of the rails, each having an integral flange at the side remote from the rail, the lateral face of the flange toward the rail being beveled toward each end thereof, a friction roller at the center of said face, and means in connection with one of the plates for securing it to the rail.

3. A car replacer comprising a pair of plates adapted to be placed along side of the rails, each having an integral flange at the side remote from the rail, the lateral face of the flange toward the rail being beveled toward each end thereof, one of said plates having brackets extending beneath the rail, and the other having a groove for receiving the rail.

WILLIAM M. ^{his} X KITCHEN.
